The ornamental design for a cutting board scraper, as shown and described.

DESCRIPTION

FIG. 1 is a front elevational view of a first embodiment of a cutting board scraper showing my new design, a rear elevational view thereof being a mirror image;

FIG. 2 is a top plan view thereof;

FIG. 3 is a bottom plan view thereof;

FIG. 4 is a right side elevational view thereof, a left side elevational view thereof being a mirror image;

FIG. 5 is a front top perspective view thereof;

FIG. 6 is a front bottom perspective view thereof;

FIG. 7 is a front bottom perspective view thereof in a using position.

FIG. 8 is a front elevational view of a second embodiment of a cutting board scraper showing my new design, a rear elevational view thereof being a mirror image;

FIG. 9 is a top plan view thereof;

FIG. 10 is a bottom plan view thereof;

FIG. 11 is a right side elevational view thereof, a left side elevational view thereof being a mirror image;

FIG. 12 is a front top perspective view thereof;

FIG. 13 is a front bottom perspective view thereof;

FIG. 14 is a front bottom perspective view thereof in a using position.

FIG. 15 is a front elevational view of a third embodiment of a cutting board scraper showing my new design, a rear elevational view thereof being a mirror image;

FIG. 16 is a top plan view thereof;

FIG. 17 is a bottom plan view thereof;

FIG. 18 is a right side elevational view thereof, a left side elevational view thereof being a mirror image;

FIG. 19 is a front top perspective view thereof;

FIG. 20 is a front bottom perspective view thereof;

FIG. 21 is a front bottom perspective view thereof in a using position.

FIG. 22 is a front elevational view of a fourth embodiment of a cutting board scraper showing my new design, a rear elevational view thereof being a mirror image;

FIG. 23 is a top plan view thereof;

FIG. 24 is a bottom plan view thereof;

FIG. 25 is a right side elevational view thereof, a left side elevational view thereof being a mirror image;

FIG. 26 is a front top perspective view thereof;

FIG. 27 is a front bottom perspective view thereof; and,

FIG. 28 is a front bottom perspective view thereof in a using position.

The broken lines shown in drawings are for illustrative purposes only and form no part of the claimed design.
